(57) **CLAIM**

The ornamental design for a charging hub for a motion capturing system as shown and described.

DESCRIPTION

FIG. 1 is an exploded top perspective view of the charging hub for a motion capturing system, shown in an environment, and according to our new design.

FIG. 2 is an exploded bottom perspective view thereof.

FIG. 3 is a top plan view thereof.

FIG. 4 is a bottom plan view thereof.

FIG. 5 is a left-side elevation view thereof. A right-side elevation view is identical to the left-side elevation view thereof; and,

FIG. 6 is a front elevation view thereof. A rear elevation view is identical to the front elevation view thereof.

In FIGS. 1 and 2, the broken lines are for the purpose of illustrating environmental structure that form no part of the claimed design.

1 Claim, 6 Drawing Sheets
